UNITED STATES PATENT OFFICE

UNCAS A. WHITAKER, OF CANTON, OHIO, ASSIGNOR TO THE WESTINGHOUSE AIR BRAKE COMPANY, OF WILMERDING, PENNSYLVANIA, A CORPORATION OF PENNSYLVANIA

DOOR-CONTROLLING VALVE DEVICE

Application filed November 1, 1929. Serial No. 404,039.

This invention relates to door controlling devices, and more particularly to the means for controlling a plurality of doors of a vehicle.

5 On vehicles, and particularly those employed in passenger service, a plurality of doors are provided, such as a front or entrance door and a rear or exit door, and under varying conditions of service, there are times when 10 it is desirable to open and close one or the other of these doors, and other times when it is desirable to simultaneously open and simultaneously close both doors.

For the purpose of controlling the operation 15 of the doors, a control valve device is provided, in which, it has heretofore been the practice to form and arrange the several co-operating parts in such a manner that all of the door opening positions will be at one side 20 of the door's closed position. This arrangement of the door controlling positions has been found to be objectionable, in that, when the front door open position is arranged in advance of the rear door open position and 25 the operator desires to open the rear door only, the control valve device must be operated through the front door open position, causing an undesired and unnecessary operation of the front door operating mechanism 30 which tends to open the front door, and in case the control valve device is operated slowly through the front door open position, the front door may be unintentionally opened or partly opened. When the control valve de- 35 vice has been operated to rear door open position, the front door operating mechanism closes or tends to close the front door, thus vibrating the door, causing undesired and unnecessary noise.

40 The principal object of my invention is to provide a door controlling valve device by which the doors of a vehicle may be selectively controlled and which will be free from the above mentioned objectionable features.

45 Another object of my invention is to provide a vehicle door controlling valve device having a doors closed position intermediate the rear door open position and the front door open position.

50 A further object of my invention is to pro-

vide a door controlling equipment for a vehicle in which the door controlling valve device is mounted on the vehicle floor where it is out of the operator's way and where it renders the operator's cab free from the control pipes leading to and from the control valve device.

Other objects and advantages will appear in the following more detailed description of the invention.

In the accompanying drawing: Figure 1 is a diagrammatic view, mainly in section, of a door controlling equipment embodying my invention; Fig. 2 is a plan view of the operating handle for controlling the operation of the equipment; and Fig. 3 is a development view of the door controlling valve device.

As shown in the drawing, the equipment may comprise a door controlling valve device 1, a front door engine 2, a rear door engine 3 and a main reservoir 4 or any other desired fluid pressure supply.

The door controlling valve device 1 may comprise a casing which may rest on and be secured to the vehicle floor in any desired manner, and contained in this casing is a rotary valve 5, the chamber 6 at the top of the rotary valve being constantly connected to the main reservoir 4 through a pipe and passage 7.

Operatively connected to the rotary valve 5, and rotatably mounted in the casing, is an operating stem 8. The upper end of this stem extends through and beyond the casing and is operatively connected to the lower end of an operating shaft 9 which, adjacent its upper end, is journalled in a bracket 10 mounted on a support 11 which may be secured to the superstructure of the vehicle in any desired manner.

Contained in a chamber 12 in the casing of the control valve device, is a sanding valve 13 which is subject to the pressure of a spring 14 also contained in the chamber, said chamber being constantly connected to the main reservoir passage 7.

The sanding valve 13 has a stem 15 which extends upwardly through the casing and is adapted to be engaged by the lower end of an operating rod 16 which is slidably mount-

ed in the casing and bracket 10. The upper end of this rod 16 is adapted to be operatively engaged by a bail 17 pivotally connected to the bracket 10.

5 Adjacent its lower end, this rod 16 is provided with a collar 18 which is adapted to engage a lug 19 on the casing to limit the upward movement of the rod and which forms a spring seat for one end of spring 20, the opposite end of the spring being seated on the casing.

10 Removably mounted on the upper end of the shaft 9, is an operating member 21 having a hinged handle portion 22 adapted to be operated in a horizontal plane for rotating the shaft 9 and in a vertical plane for controlling the operation of the sanding bail 17.

15 The door engines 2 and 3 may be of the usual type and each may comprise a casing containing a door opening piston 23 and a door closing piston 24, which pistons are connected together by a toothed bar 25, the teeth of which mesh with the teeth of a gear segment 26 operatively connected with an operating shaft 27 of the usual door operating mechanism.

20 According to my invention, the doors closed and handle off position is the same and is between the rear door open position and the front door open position, as shown in Fig. 2 of the drawing.

25 With the door controlling valve device in doors closed position as shown in Figs. 1 and 2, fluid under pressure is supplied from the rotary valve chamber 6 to the door closing sides of the door engines 2 and 3 by way of a port 28 in the rotary valve 5 and passages and pipes 29 and 30 respectively, and the door opening sides of the engines are connected to the atmosphere through pipes and passages 31 and 32 respectively, a cavity 33 in the rotary valve 5 and an atmospheric passage and pipe 34. With the door opening sides of the door engines vented and the door closing sides supplied with fluid under pressure, both doors will be maintained closed.

30 When it is desired to open the rear door only, the control valve device is operated toward the left from doors closed position to rear door open position in which the door closing side of the door engine 3 is vented to the atmosphere by way of pipe and passage 30, a cavity 35 in the rotary valve 5 and passage and pipe 34, and the door opening side of the door engine is supplied with fluid under pressure from the rotary valve chamber 6 by way of a port 36 in the rotary valve 5 and passage and pipe 32.

35 With the control valve device in rear door open position, the pressure of fluid in the door closing side of the front door engine 2 is maintained through the port 36 in the rotary valve and the door opening side of this engine is maintained connected to the atmos-

phere through the cavity 35 in the rotary valve, so that the front door will be maintained closed.

40 When it is desired to open the front door only, the control valve device is operated toward the right, from doors closed position to front door open position in which the door closing side of the front door engine 2 is vented to the atmosphere by way of pipe and passage 29, a cavity 37 in the rotary valve 5 and passage and pipe 34, and the door opening side of the door engine 2 is supplied with fluid under pressure from the rotary valve chamber 6 by way of a port 38 in the rotary valve and the passage and pipe 31.

45 With the control valve device in front door open position, the pressure of fluid in the door closing side of the rear door engine is maintained by way of the port 38 in the rotary valve 6 and the door opening side of this engine is maintained vented to the atmosphere by way of the cavity 37 in the rotary valve, so that the rear door is maintained closed.

50 When it is desired to open both doors simultaneously, the control valve device is operated to doors open position in which the door closing sides of both door engines are connected to the atmosphere by way of a cavity 39 in the rotary valve 5, and fluid under pressure from the rotary valve chamber 6 is supplied to the door opening sides of both engines through a port 40 in the rotary valve 5.

55 It will be noted from the foregoing description that with my improved equipment, one door may be opened without having to operate the control valve device through the door opening position of the other door, thus maintaining said other door closed.

60 In any position of the control valve device, the operating handle 22 may be depressed to cause the track rails, upon which the vehicle runs, to be sanded. The depression of the handle causes the bail 17 and operating rod 16 to move downwardly against the pressure of the spring 20, unseating the sanding valve 13 against the pressure of the spring 14.

65 Upon the relief of pressure on the handle 22, the pressure of the spring 20 causes the rod 16 and bail 17 to move upwardly to their normal positions, permitting the pressure of the spring 14 to seat and close off the further supply of fluid under pressure to the sand traps.

70 By mounting the control valve device on the vehicle floor, the operator's cab will be free from all of the pipes leading to and from the control valve device, thus providing 75

more room for the operator to control the operation of the vehicle and rendering the cab more sightly.

While one illustrative embodiment of the invention has been described in detail, it is not my intention to limit its scope to that embodiment or otherwise than by the terms of the appended claims.

Having now described my invention, what is claimed as new and desired to be secured by Letters Patent, is:

1. The combination with a mechanism for operating a plurality of doors of a vehicle, of a manually operative device for controlling said mechanism to selectively operate said doors, said device having a plurality of door opening positions and a door closing position intermediate two of said door opening positions in which door closing position said mechanism is controlled to close any door which is open, said positions being in uninterrupted succession.

2. The combination with a fluid pressure equipment for operating a plurality of doors of a vehicle, of a valve device operative for controlling said equipment to selectively operate said doors, said valve device having two door opening positions and a door closing position intermediate said door opening positions in which door closing position said mechanism is controlled to close any door which is open, said positions being in uninterrupted succession.

3. The combination with a fluid pressure equipment for operating a front door and rear door of a vehicle, of a valve device having one position for controlling said equipment to open said front door and another position for controlling said equipment to open said rear door, and having a position intermediate the door opening positions for controlling said equipment to close either of said doors.

4. The combination with a fluid pressure equipment for operating a front door and rear door of a vehicle, of a door engine for operating the front door, a door engine for operating the rear door, and a valve device for controlling the operation of said door engines, said valve device having one position for causing the front door engine to operate to open the front door and for maintaining the rear door engine inactive to open the rear door, a position for causing the rear door engine to operate to open the rear door and for maintaining the front door engine inactive to open the front door and a position intermediate the door opening positions for operating the engine which is in door open position to door closed position and for maintaining both of said engines in door closed positions.

5. In a door controlling and track rail sanding equipment for a vehicle, the combination with the floor of the vehicle, of a

door controlling valve device mounted on said floor, a normally seated sanding valve included in said door controlling valve device, a bracket mounted on the vehicle above said valve device, a rotatable shaft operatively connected to said valve device and journaled in said bracket, a rod slidably mounted in said bracket and door controlling valve device operative downwardly to unseat said sanding valve to supply fluid under pressure to sand the track rails and operative upwardly to permit the sanding valve to seat and close off the supply of fluid under pressure, and a handle operative in a horizontal plane for rotating said shaft and operative in a vertical plane for controlling the operation of said rod.

6. In a door controlling and track rail sanding equipment for a vehicle, the combination with the floor of the vehicle, of a door controlling valve device mounted on said floor, a normally seated sanding valve included in said door controlling valve device, a bracket mounted on the vehicle above said valve device, a rotatable shaft operatively connected to said valve device and journaled in said bracket, a rod slidably mounted in said bracket and door controlling valve device operative downwardly to unseat said sanding valve to supply fluid under pressure to sand the track rails and operative upwardly to permit the sanding valve to seat and close off the supply of fluid under pressure, a bail pivotally mounted on said bracket adapted to operatively engage said rod, and a handle operative in a horizontal plane for rotating said shaft and operative in a vertical plane for controlling the operation of said bail and rod.

7. The combination with a fluid pressure equipment for operating two doors of a vehicle, of a valve device for controlling said equipment to open and close said doors selectively, said valve device having a door opening position for each door and a single door closing position, to which latter position, said valve device is operative from either door opening position without passing through any other door controlling position.

8. The combination with a fluid pressure equipment for operating two doors of a vehicle, of a valve device for controlling said equipment to open and close said doors selectively, said valve device having a door opening position for each door and a single door closing position, in which latter position said equipment is operated to close either of said doors and to which said valve device is operative from either door opening position without passing through the other door opening position.

In testimony whereof I have hereunto set my hand, this 29th day of October, 1929.
